ATTORNEY

UNITED STATES PATENT OFFICE.

KARL BOMHARD, OF MUNICH, GERMANY, ASSIGNOR, BY MESNE ASSIGNMENTS, TO
FREDERICK PFEIFFER & CO. INC., OF NEW YORK, N. Y.

VAGINAL SYRINGE.

Application filed May 8, 1922. Serial No. 559,295.

To all whom it may concern:

Be it known that I, KARL BOMHARD, a citizen of the German Republic, residing at Munich, Germany, have invented certain new and useful Improvements in Vaginal Syringes, of which the following is a specification.

This invention has reference to improvements in vaginal irrigating syringes and relates more specifically to a device of the return-flow character, in which the cleansing or medicinal fluid is introduced at the front end of the vagina and is withdrawn again therefrom at the innermost portion after having been in intimate contact with the entire surface of the vagina, special means being provided to prevent the flesh folds from occluding the outlet orifice of the syringe, which would prevent the fluid from running off.

The device, which may be in the main of any suitable material, preferably hard glass, can readily be taken apart for cleaning purposes and, as there are no valves or other movable parts, it is not liable to get out of order.

My invention will best be understood from the accompanying drawing, in which Fig. 1 shows a side elevation, partly in section, of the new syringe; Fig. 2 is a section on line 2—2 of Fig. 1, and Fig. 3 shows diagrammatically how the syringe is connected in use with the supply and waste receptacles respectively.

The device essentially comprises the outer inflow or mantle member 1 from which laterally communicatingly extends the nipple branch member 2, and the outflow member 3 arranged within the member 1 with capability of relative axial and rotary displacement. The inflow member 1 is contracted at its one end, as at 4, and it is provided at its other end with inwardly directed inter-spaced projections 5, obtained by correspondingly depressing the tube wall to provide seating recesses for the thickened rim 6 of a bell-shaped cuff or shield 7 of suitable material, preferably soft rubber, designed to occlude the mouth of the vagina for preventing leakage therefrom of the douching fluid.

I may also see fit to dispense with such a separate occluder and integrally form the tube end into proper bell shape, though, obviously, the yieldable rubber cuff would generally be preferred. The cuff normally

makes a tight joint with the tube 1, but the parts for cleaning and other purposes can at all times readily be disconnected and connected again by snapping the cuff rim out of or into the wall depressions.

The liquid entering the tube 1 through the branch tube 2 from a supply receptacle 11 (Fig. 3) readily passes out in the direction of the arrows *a* in Fig. 1 between the support knobs 5, which latter serve to retain the inner outflow tube 3 in concentrical, spaced relation to the outer tube. The outflow tube which is open at both ends extends clear through and considerably beyond the two ends of the outer tube and its forward end is preferably slightly curved to the anatomical conformation of the vagina. To prevent the forward outflow orifice of the tube 3 from becoming closed by overlying flesh folds, which, obviously, would at once stop the device from functioning properly, there is provided at this end a guard member or spreader head 8, as shown by way of example in the shape of a crown formed of bow-shaped rods which, preferably integrally, extend from near the extremity of the tube 3 and are spaced apart therefrom both longitudinally and cross-wise at the point of juncture somewhat in advance of the tube orifice.

The constricted end 4 of the tube 1 is air- and fluid-tightly, yet yieldably connected with the snugly nested tube 3 by means of a rubber sleeve or cuff 8, which allows of the tube 3 being relatively displaced within the tube 1 both rotatally and longitudinally. An electrode 10 may be provided in the tube 1 for introducing electrical currents of different character, as well known in the respective arts.

In use the tube 3 is inserted into the vagina with the rubber cuff tightly closing the entrance thereof, the branch tube 2 being connected by tubing 12 with the tank 11. By relative displacement of the inner tube 3 within the outer tube the spreader crown may be adjusted to various positions within the vagina, for directing or restricting the douche fluid to distinct portions of the vagina.

The liquid passes through the passages formed between the two nested tubes 1 and 3 by the knobs 5 into the vagina and is withdrawn therefrom through the tube 3, as indicated by the curved arrows. The de-

gree of force and the velocity with which the fluid passes through can be regulated and controlled by proper manipulation of the supply tank 11 or the receptacle 13 intended 5 to receive the spent fluid. In the diagrammatic Figure 3 the principle of such control is illustrated. If the waste receptacle 13 is held in the relative position I, the discharge flow will be less accentuated than with the 10 receptacle in position II, it being understood that the outlet end of tube 3 is connected to the receptacle 13 by tubing 14. As there is no internal pressure to overcome, owing to the complete absence of air pockets or other 15 resistance, the whole system thus being at all times under atmospheric pressure, any change in the relative position of the receptacles will only alter the rate of flow of the liquid. It is thus possible by positioning 20 supply tank, waste tank and syringe on practically the same level to retain the liquid stationary within the vagina for any desired period.

Though I have described and shown the 25 new device as introducing the douche fluid through the outer member and withdrawing it again through the inner member, I want it to be particularly understood that I can just as well cause the fluid to flow in reverse 30 direction, that is to say, I can introduce it through the inner member and run it off again through the outer member, without in any way interfering with the underlying 35 theoretical considerations or affecting the specific construction of the device. I am, however, satisfied that to reverse the flow of 40 the irrigating fluid will, to some extent, lower the efficiency of the operation, and for this reason I have specifically described the more efficient procedure.

What I claim is:—

1. In a device of the character set forth,

in combination, a relatively short inflow member open at the front end and presenting a constricted rear portion, an occluder 45 mounted on the front end of said inflow member, interspaced centering projections extending from the inner wall of said inflow member near its open end but rearwardly therefrom, means for holding the occluder in operative position, a relatively extended outflow member concentrically spaced 50 edly supported within said inflow member by said inflow member constriction and said inflow member projections, and a connecting elastic sleeve embracing both said inflow member constriction and said outflow member.

2. In a device of the character set forth, 60 in combination, a relatively short inflow member open at the front end and presenting a constricted rear portion, interspaced centering projections integrally extending from the inner wall of said inflow member near its open end and obtained by correspondingly depressing the inflow member wall thereby forming depressions exteriorly 65 of said member, a resilient frusto-conical occluder cuff adapted to readily detachably cooperate with said inflow member depressions, a relatively long outflow member slightly curved at its free forward portion and adapted to be concentrically supported within 70 said inflow member by said inflow member constriction and said inflow member 75 projections, and a rubber sleeve fluid-tightly connecting the constricted portion of said inflow member with said outflow member with capability of relative longitudinal and rotary displacement, and a spreader means 80 surrounding the front end of said outflow member.

In testimony whereof I affix my signature.

KARL BOMHARD.
